UNITED STATES PATENT OFFICE.

JOHN C. KAISER, OF KENTON, OHIO.

DESIGN FOR A VEHICLE-BODY.

No. 39,266.

Specification for Design.

Patented April 14, 1908.

Application filed February 8, 1908. Serial No. 414,988. Term of patent 3½ years.

To all whom it may concern:

Be it known that I, JOHN C. KAISER, citizen of the United States, residing at Kenton, county of Hardin, and State of Ohio, have invented a new and original Design for Vehicle-Bodies, of which the following is a specification, reference being had to the accompanying drawing, forming part thereof, in which the figure is a perspective view of a vehicle-body showing my new design.

I claim:
The ornamental design for a vehicle body, as shown.

JOHN C. KAISER.
